UNITED STATES PATENT OFFICE.

THOMAS JAMES RAYNER, OF LONDON, ENGLAND.

SURFACE CONDENSER.

SPECIFICATION forming part of Letters Patent No. 468,048, dated February 2, 1892.

Application filed August 11, 1891. Serial No. 402,386. (No model.) Patented in England April 21, 1888, No. 5,972.

To all whom it may concern:

Be it known that I, THOMAS JAMES RAYNER, a citizen of England, residing at No. 777 Commercial Road, in the county of London, England, have invented a new and useful Surface Condenser, (for which I have obtained a patent in Great Britain, dated April 21, 1888, No. 5,972,) of which the following is a specification.

10 My invention relates to a construction of surface condenser consisting of a number of tubes coiled in volute form and connected together within a casing supplied with water surrounding the tubes, so that steam passed 15 through these coils becomes condensed, heating the surrounding water for use as boiler-feed or generating vapor from it to be condensed as distilled water.

Figure 1 of the accompanying drawings is 20 a vertical section, and Fig. 2 is a sectional plan on the line 2 2 of Fig. 1, of a surface condenser according to my invention, arranged to operate for distillation of sea-water.

A is a casing, preferably of cylindrical form 25 and provided with tightly-closing covers at top and bottom and having on its top cover a safety-valve B, a pressure-gage C, and a stop-valve D. The lower part of the casing is occupied by a number of pipes (preferably of 30 thin copper) E' E² E³, &c., coiled in volute form, all these coils being attached to a cover F, which is bolted to flanges at one side of the casing. By unscrewing the bolts the cover F, with the coils attached to it, can be removed from the casing, so that the coils can 35 be cleaned or repaired when necessary. In the cover F, at one side of it, there are formed a number of cavities f' f² f³ f⁴, according to the number of coils E' E², &c. The uppermost cavity f' communicates with a passage 40 from an inlet G for steam. The lowest cavity f⁴ communicates with a similar passage to an outlet for water of condensation. One end of the uppermost coil E' is jointed to f' and 45 one end of the lowest coil E⁶ is jointed to f⁴. Of the other coils the ends of E² and E³ are both jointed to f² and the ends of E⁴ and E⁵ are both jointed to f³. The inner ends of the coils are jointed to junction-cavities K', receiving the ends of E' and E², K² receiving the ends of E³ and E⁴, K³ receiving the ends of E⁵ and E⁶. Thus steam entering from G

to f' passes inward through the uppermost coil E' to K', thence outward through the coil E² to f², thence inward through E³ to K², 55 and so on, taking a zigzag course inward through the one coil and outward through the next coil below to the last cavity f⁴. Obviously there might be a greater or less number of pairs of coils, the connecting-cavities 60 f and K being arranged accordingly.

At the side of the casing A is fixed a feed-cistern H, furnished with a ball-cock or float-valve, by which the water to be distilled is admitted to maintain its level within the casing a little above the uppermost coil E'. Several perforated plates I and baffle-plates J may be arranged, as shown, in the upper part of the casing to prevent water from priming over with the vapor generated. This vapor 70 passes away by the valve D to any suitable condenser, the resulting water being used either for drink or for feeding boilers with fresh water at sea. In the latter case the vapor generated may pass to the main condenser, so that the evaporation goes on under 75 greatly-reduced pressure.

When the apparatus is used as a condenser or feed-water heater, the casing need not extend much above the uppermost coil, cold 80 water being supplied to it near its bottom and the heated water being conducted away from its top.

Having thus described the nature of this invention and the best means I know for carrying the same into practical effect, I claim—

1. A surface condenser comprising a series of pipes, each pipe of the series coiled in volute form and the whole arranged one above the other to form a stack of volute coils one 90 above the other, communicating with one another for the passage of steam from one to the other from one end of the stack to the other consecutively through each coil of the series, substantially as and for the purposes set forth. 95

2. A surface condenser comprising a series of volute coils of pipe arranged one above the other and communicating with one another, a chamber inclosing said volute coils, and a removable cover having the series of volute 100 coils connected thereto, substantially as and for the purposes set forth.

3. A surface condenser comprising a series of volute coils arranged one above the other,

junction-cavities connecting the inner ends of pairs of the coils for the passage of steam from one volute coil to the other of the pair, and junction-cavities connecting the outer 5 end of one coil with the outer end of a coil adjacent thereto, substantially as and for the purposes set forth.

4. A surface condenser comprising a series of volute coils of pipes communicating with 10 one another for the passage of steam from one end of the stack to the other consecutively through each coil of the series and arranged one above the other, a chamber inclosing said coils, a feed-cistern communicating with said 15 inclosing chamber and provided with an automatically-acting valve to maintain a level of water in said chamber, and an outlet for

the water of condensation from said volute coils of pipes, substantially as and for the purposes set forth. 20

In testimony whereof I have signed my name to this specification, in the presence of two subscribing witnesses, this 31st day of July, A. D. 1891.

THOMAS JAMES RAYNER.
